CLAIM

What is claimed is the ornamental design for a shoe, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a right side view of a first embodiment of a shoe, showing our new design;

FIG. 2 is a left side view thereof;

FIG. 3 is a front view thereof;

FIG. 4 is a rear view thereof;

FIG. 5 is a top view thereof;

FIG. 6 is a bottom view thereof;

FIG. 7 is a right side view of a second embodiment of a shoe, showing our new design;

FIG. 8 is a left side view thereof;

FIG. 9 is a front view thereof;

FIG. 10 is a rear view thereof;

FIG. 11 is a top view thereof; and,

FIG. 12 is a bottom view thereof.

The grayed out portions surrounded by dot-dot broken lines illustrate portions of the shoe that form no part of the claimed design.
